UNITED STATES PATENT OFFICE.

FRANK E. BURLEY, OF CHICAGO, ILLINOIS.

DESIGN FOR A PITCHER.

SPECIFICATION forming part of Design No. 29,757, dated December 6, 1898.

Application filed June 20, 1898. Serial No. 684,001. Term of patent 7 years.

To all whom it may concern:

Be it known that I, FRANK E. BURLEY, a citizen of the United States, residing at Chicago, in the county of Cook and State of Illinois, have invented a new and useful Design 5 in Pitchers, reference being had to the accompanying drawings, forming a part hereof.

Application for design patent was filed in Great Britain May 31, 1898, No. 319,713.

10 In the accompanying drawings, Figure 1 represents a side elevation of the obverse side of a pitcher embodying my design, and Fig. 2 a similar view of the reverse side of the pitcher.

15 The leading features of my design consist in the pitcher provided with a handle portion the upper part of which is the bust of a human figure, the side portions of the pitcher having Indian heads thereon and the spout

or front portion of the pitcher provided with 20 a head of a human figure.

A is the pitcher; B, the handle portion; C, the image of a human bust on the upper part of the handle, connecting it to the body portion; D D', the representations of Indian 25 heads on the body of the pitcher; and E, the image of a human head on the spout of the pitcher, the whole presenting to the eye a harmonious and ornate figure, as shown in the accompanying drawings. 30

I claim—

The design for a pitcher substantially as shown and described.

FRANK E. BURLEY.
